ERNESTO CURTI, OF MILAN, ITALY

PNEUMATIC TOOL OPERATING APPARATUS

Application filed February 27, 1928, Serial No. 257,441, and in Italy February 28, 1927.

The invention relates to aerodynamic machines of the kind in which the air pump or better the pneumatic driver supplies compressed air, the amount of which is limited to the requirements of the machine tool or tools connected thereto by pipings. In the connecting piping of all machines of this kind heretofore known there is a succession of compression and suction phases corresponding to the succession of the pneumatic phases in the driver, that is to say, the air which in the compression phase is forced towards the tool, is afterwards sucked back into the piping. This is a serious inconvenience and a useless, and harmful, recuperation of fluid because, owing to the fact that it is more difficult to suck a fluid column in a piping than to compress it, the machine tools must be installed relatively near to the driver in order to avoid an excessive length of such pipings; the piping must not exceed a certain limit in length, because beyond such a limit the suction is no longer practicable.

The driving arrangement for pneumatic tools according to the invention fully obviates these inconveniences and essentially distinguishes itself by the fact that in the piping connecting the machine tools to the driver the air is actuated only in the direction from the driver towards the machine tools and this pressure impulse brings about the tool's operative stroke, whereas the idle stroke is operated either by another pneumatic pressure impulse or by a mechanical agent, for instance a spring, that comes into action as soon as the air pressure ceases and the air discharges itself to the atmosphere.

The driving device according to the invention is schematically illustrated by the annexed drawing, in which

Fig. 1 is a vertical longitudinal sectional view of one form of the invention, and

Fig. 2 is a fragmentary sectional view of another form.

Referring to Fig. 1, A represents the pneumatic driver, B a machine tool, C the piping connecting the two together, D the tool proper.

The driver A, the piston 1 of which may

fitted with a valve 2 through which the outer air is drawn in and with a valve 3 through which the compressed air is forced into the connecting piping C; this compressed air cannot return into the pump body, because the valve 3 is closed during the suction phase.

The air is delivered by the piping C into a chamber 4 of the machine tool B, in which a distributor 5 is adapted to slide. The distributor 5 is constantly acted upon by a spring 6 tending to force it towards the air inlet so that the incoming air, with its pressure, forces the distributor 5 to the left against the action of the spring. The various parts are so designed that in this backward stroke of the distributor 5 one of the ports 7 provided in the distributor wall registers with the port 8 opening into the body 9 in which the striking mass 10 is adapted to reciprocate.

In the hollow distributor 5 a partition 11 is provided by which the distributor chamber is divided in two, namely one portion receiving the air supplied by the piping C and the other intended to receive the air that discharges itself from the body 9 through the opening 12 after having performed work. Beside the ports 7 already mentioned, further ports 13 are provided in the distributor wall, adapted to communicate, in the manner that will be described hereinafter, with the chamber 14 of the machine tool 8, the lower end of the chamber 14 opening into the chamber 9 for the purpose of bringing the striking mass 10 back into its highest position. The distributor 5 is firmly provided with yet another set of ports 15 adapted to set the discharge ports 12 into communication with the rear chamber of the distributor and therewith the outlet to the atmosphere, which takes place through the ports 16 of the chamber in which the distributor is slidably mounted.

Beside the rectilinear reciprocating motion, the distributor 5 is adapted to perform a revolving motion; it can revolve during the forward motion caused by the spring 6 when the air pressure ceases. In the example shown, the distributor 5 is slipped on a spindle 17 solid with a ratchet wheel 18 co-

- operating with a ratchet 19. The wheel 18, and therewith the spindle, can revolve in one direction only, namely when the distributor 5 pushed by the air pressure, moves in backward direction. During this stroke, due to the screw-threading 20 with which the spindle 17 is provided, the distributor 5 and the spindle 17 are kinematically coupled up with one another so that, as the spindle can turn, the distributor slides without revolving. On the return stroke on the contrary, due to the ratchet 19, the screwthreaded spindle 17 is prevented from turning so that the distributor 5, beside its axial movement, is obliged to revolve through a fraction of a turn so as to bring a port 15 into register with an outlet port 12, and a port 13 into register with the chamber 14 opening into the chamber 9 below the striking mass 10.
- 20 To ensure proper registration of ports 7 with ports 8 or of ports 13 and 15 with passages 14 and 12 it is sufficient to provide the gear wheel 18 with six teeth when there are nine ports.
- 25 The pawl 19 will snap into the tooth-space of one of the teeth in any case, provided an accurate registration exists between one of the ports of the valve 5 and the corresponding ports 12, or 8 etc. of the body B.
- 30 Even granting that a certain angular offset may exist due to the friction of the shaft 17 in its bearings, yet since the pawl 19 cannot possibly stop half-way of the tooth-flank but must necessarily engage one tooth or the other the corresponding ports will always register with one another.
- 35 This fact has been positively ascertained in actual practice because the spring that urges the pawl 19 acts upon this pawl and therewith also on the gear wheel 18 in such a manner as to correct the eventual off-set caused by friction.
- 40 After the above description, the working of the arrangement will readily be understood.
- 45 Let the piston 1 be moved upwardly; the suction valve 2 will close and the delivery valve 3 will open. The compression impulse will transmit itself through piping C and reach the forward chamber of the distributor; forcing the latter to the left as shown in Fig. 1 and when in such extreme position all ports 13 are closed while one of the ports 7 communicates with the port 8 so that the impulse will simultaneously with the initial movement of the distributor enter the body 9 and force the striking mass 10 downwardly, thus actuating the tool proper D. After this the piston 1 commences a further stroke 50 in order to draw in air through the suction valve 2; simultaneously the delivery valve 3 closes and advantageously prevents the air from rushing back from the piping C. The piston 1 then compresses the air again and 55 sends another compression impulse into the

piping C. The air thus forced, no longer finds its exit through a port 7 but through a port 13, because the distributor in the meantime, has resumed its former axial position under the action of the spring 6 and by reason of a bleed opening 6' and, by effect of the screw-threaded spindle 17, has undergone an angular displacement so as to close the ports 7 and to bring a port 13 into communication with the chamber 14 and a port 15 into register with the outlet opening 12. As a consequence, the compressed air delivered by the piping C will impinge against the underface of the striking mass 10 and force it upwardly into its rest position, and thus oblige the air enclosed in the chamber 9 to escape to the atmosphere through 12-15-16. It will readily be understood that in the successive compression phases of the piston 1 the compressed air will find open a port 8 and so on.

Since in order to raise the striking mass 10 a small air pressure is sufficient, the wall of the body in which the striking mass is reciprocating is provided with openings 21 through which the compressed air can freely escape.

As regards the cross-sectional area of the ports 21, it is to be noted that in order to raise the piston 10, a relatively small pressure is sufficient, because the upward stroke of the piston is not an operative stroke. Accordingly, the pressure that remains in the chamber underlying the piston 10 (difference between the pressure of the fluid entering 100 through 14 and the pressure of the fluid leaving through port 21) is sufficient to raise the piston.

Even medium large ports 21 may be provided because they remain always open and consequently a longer time is available for the fluid to discharge itself to atmosphere. For this reason, even if in the chamber underlying the piston a certain pressure is left in excess of atmospheric pressure, it is readily overcome by the pressure exerted in downward direction on the operative stroke.

The modified construction according to Fig. 2 differs from the foregoing one in that the striking mass 10' is brought back into its normal position, ready for receiving the impulse, by a spring 22 instead of by pneumatic action. Of course the adoption of this mechanical means involves some modifications also in the distributor 5' inasmuch as its revolving movement is no longer required. In this case the distributor comprises an inlet chamber 23 and an outlet chamber 24 and is placed under the action of a spring 6' tending to move the distributor in opposite direction to that of the air impulse. When an air impulse takes place, the distributor moves backwardly and causes the inlet chamber 23 to communicate with the inlet opening 8' the striking mass 10' being thus sharply 130

forced downwardly and the spring 6' compressed. As soon as the compression action of the piston 1 ceases, the striking mass 10' rises and causes the air to discharge itself through the outlet opening 12' which is now in communication with the outlet chamber 24 of the distributor 5'. The initial conditions are thus restored and the described cycle repeats itself over again.

From the abovesaid it will be apparent that in the connecting piping C, C', rather than a travelling motion in the direction from the driver or pulsator towards the machine tool, there takes place a series of extremely quick compression impulses that transmit themselves to the distributor and to the striking mass. In order that the antagonistic spring 6, 6' may readily exercise its action as soon as the compression impulse ceases, the vent or narrow bleed opening 6'' is provided, this opening setting the inside of the connecting piping into communication with the atmosphere and allowing the discharge of the over-pressure that remains in said piping.

In a general way, the details may be varied as will be found convenient without departing from the spirit and scope of the invention.

What I claim is:

1. In combination a pneumatic driver including a piston and a valve controlled compressed air supply pipe, a machine tool connected to the supply pipe and including a piston, and a rotatably mounted distributor also movable in one direction in the tool in response to each pressure applying impulse of the driver piston and provided with ports certain of which control the admission of compressed air to the piston in the tool so that the latter is given its operative stroke simultaneously with the pressure applying impulse of the driver piston, the remaining ports of the distributor acting to control the application of a second impulse on a tool piston for returning the latter to its original position during the rotation of said distributor.

2. An arrangement as claimed in claim 1, wherein spring means is provided for acting on the distributor in a direction opposite the pressure applying impulse of the compressed air.

3. An arrangement as claimed in claim 1, wherein the tool is provided with a chamber having ports communicating with the respective ends of the piston, and the distributor being mounted in the chamber so that its ports may be successively and alternately brought into registration with the ports in the chamber which communicate with the piston, substantially as and for the purposes set forth.

4. In combination a pneumatic driver including a piston and a valve controlled compressed air supply pipe, a machine tool con-

nected to the supply pipe including a casing providing a cylinder having a chamber adjacent one end of the cylinder and also provided with ports establishing communication with the respective ends of the cylinder, a piston in the cylinder, a distributor mounted to reciprocate and partially turn in said chamber and provided with ports which are adapted to register at times with the ports leading to the respective ends of the cylinder, said distributor being movable in one direction in response to each pressure applying impulse of the driver piston to alternately move the tool piston in opposite directions, and spring means acting on the distributor in a direction opposite the pressure applying impulses.

5. An arrangement as claimed in claim 1, wherein the distributor includes a stem having a spiral thread, a body having the ports therein mounted on the thread on the stem, and pawl and ratchet mechanism for permitting rotation of the stem in only one direction, substantially as and for the purposes set forth.
